United States Patent Office

Des. 190,739
Patented June 27, 1961

190,739

BANNER

Anna Mae Wolff, 3131 Zenobia St., Denver, Colo.

Filed Jan. 11, 1960, Ser. No. 59,010

Term of patent 7 years

(Cl. D29—17)

The drawing is a face view of a banner showing my new design. It has no appreciable thickness and the rear thereof is plain and unadorned.

The dominant features of my design are shown in full lines.

I claim:

The ornamental design for a banner, as shown and described
